UNITED STATES PATENT OFFICE.

ROCKWELL L. GALLUP, OF CHICAGO, ILLINOIS, ASSIGNOR TO NATIONAL BOTTLERS EQUIPMENT COMPANY, A CORPORATION OF ILLINOIS.

BOTTLE-WASHING MACHINE.

1,076,277.

Specification of Letters Patent.

Patented Oct. 21, 1913.

Application filed February 5, 1912. Serial No. 675,484.

To all whom it may concern:

Be it known that I, ROCKWELL L. GALLUP, a citizen of the United States, residing at Chicago, in the county of Cook and State of Illinois, have invented certain new and useful Improvements in Bottle-Washing Machines, of which the following is a specification:

This invention relates to bottle washing machines and aims to provide an automatically operated machine of simple but substantial construction which will thoroughly cleanse and rinse the bottles after they have been placed on the carrier and without further attention on the part of the operator.

One of the objects of the present invention is the provision of a machine of this general character which shall be as small and compact as is consistent with the work required, the compactness of the machine being facilitated by mounting the bottle carrier entirely above the washing and controlling mechanism thereby reducing to a minimum the length of the carrier and the size of the wheels around which it travels.

Another object is the provision of hydraulic means for intermittently actuating the carrier to move the bottles forward step by step.

Still another object is the provision of a single controlling valve for controlling and timing the operation of the washing and rinsing spindles, the raising and lowering of the same and the intermittent actuation of the carrier.

Other objects and advantages will be readily apparent as the invention becomes better understood by reference to the following description when considered in connection with the accompanying drawings illustrating one practical embodiment thereof.

Referring to the drawings—Figure 1 is a plan view of a bottle washing machine equipped with my invention; Fig. 2 is a side elevation thereof; Fig. 3 is a transverse sectional view taken substantially on the line 3—3 of Fig. 1; Fig. 4 is a sectional view of the carrier and the hydraulic cylinders for actuating the same, taken substantially on the line 4—4 of Fig. 1; Fig. 5 is a detail sectional view of one of the hydraulic raising and lowering cylinders; Fig. 6 is a fragmentary sectional view through the upper and lower travels of the carrier and one of the shooting spindle nozzles; Fig. 7 is an

enlarged sectional view of the shooting spindle nozzle shown in Fig. 6; Fig. 8 is a fragmentary plan view of one end of the machine showing the controlling valve; Fig. 9 is a longitudinal sectional view taken substantially on the line 9—9 of Fig. 8; and Figs. 10, 11, 12, 13 and 14 are transverse sectional views of the controlling valve taken substantially on the lines 10—10; 11—11; 12—12; 13—13 and 14—14, respectively, of Fig. 9.

On the drawings, reference character 15 designates the base of the machine which is preferably made of hollow construction to form a chamber or receptacle 16 for the storage of the water which is used repeatedly in the shooting spindles, the raising and lowering cylinders and in the carrier feeding cylinders. Standards or uprights 18 are supported on the base and carry on their upper ends longitudinally extending castings or frames 19 upon which the bottle carrier and the mechanism for operating the same are mounted. A shaft 21 journaled at one end of the frames 19 carries sprocket wheels 22 and a similar shaft 23 journaled at the other end of the frame 19 in adjustable bearing blocks 24 carries similar sprocket wheels 26, the endless bottle carrier hereinafter described being adapted to encircle the sprockets 22 and 26. The blocks 24 are slidably mounted in guides in the frame ends and are normally urged outwardly to exert tension on the carrier by expansion springs 20, the tension of which may be regulated by adjusting screws 25.

The bottle carrier itself comprises preferably a series of transversely extending bars 27 which are secured at their ends to chains 28, the bars being preferably secured to the chains so that they are positioned intermediate the ends of each link. The pivot pins 29, connecting the various links of the chains, are equipped with bearing rollers 31 adapted to be supported by and travel along the upper and lower tracks 32 and 33, respectively, formed by the frames 19. The sprocket wheels around which the endless carrier travels, as will be observed from the drawings, are of comparatively small size so that the upper and lower travels of the carrier are spaced apart but a short distance thereby enabling the entire carrier to be positioned above the washing spindles instead of having the spindles located between the

85

upper and lower travels of the carrier as has been customary in machines of this character heretofore employed.

Each cross-bar 27 is equipped with a plurality of bottle receiving sockets, designated generally as 34, said sockets being either cast integrally with the bar or attached thereto, as preferred, the individual sockets and bottle receiving portions 35 extending on one side of the bar, as shown in Fig. 6, and a flared portion 36 projecting from the opposite face of the bar, the flared portion being adapted to serve as funnels or collectors to collect the shot discharged from bottles being cleansed and positioned in the sockets of the upper travel of the carrier, as will be hereinafter described. The shooting spindles 37, of which there are preferably four rows and the rinsing spindles 38, of which there is preferably one row, are normally located beneath the lower travel of the carrier, as shown in Figs. 2 and 3, and in order to reduce the length of travel of the spindles, thereby increasing the speed of the machine, the bottle holding portion of each of the sockets is provided with a longitudinally extending slot 39 into which the upper ends of the spindles project as the carrier is being moved along. While I have shown in the present instance four rows of shooting spindles and one row of rinsing spindles it will be obvious that the number of rows may be increased or diminished, if desirable.

The carrier is so proportioned that the bottle receiving sockets on the upper and lower travels of the carrier will be positioned in vertical alignment above the shooting and rinsing spindles after each actuation of the carrier so that the spindles can be projected through the aligned sockets into the inverted bottles carried by the upper sockets, the spindles in their raising and lowering movements passing entirely through the sockets on the lower travel of the carrier and when lowered assuming the position shown in Figs. 2 and 3 with their upper ends projecting into the slots 39 of the lower sockets, as previously described. The carrier is moved forward by suitable mechanism which imparts an intermittent or step by step movement to the carrier between the successive operations of the spindles. The carrier actuating mechanism as shown comprises a pair of reciprocatory rods or plungers 41 mounted above the upper travel of the carrier and provided with pivotally mounted dogs 42 adapted to engage with the rollers 31 of the carrier chains to move the chain forward a predetermined distance at each reciprocation of the rods. The dogs are preferably pivotally mounted on adjustable collars or clips 43 which are capable of adjustment longitudinally of the rods 41 into required position. The rear ends of the rods 41 project into hydraulic

cylinders 44 and are equipped with suitable pistons 45 operating in said cylinders. The opposite ends of the rods project into the return cylinders 46 in which are positioned suitable expansion return springs 47 adapted to act against heads 48 mounted upon the ends of the rods 41 to return the rods after each actuation thereof by the hydraulic cylinders. In order to limit the operative movement of the rods 41 stop collars 49 may be fixed on the rods in position to abut against the ends of the return cylinders 46 thereby limiting the stroke of the rods. Water under pressure is supplied to the hydraulic cylinders through supply pipes 51 at certain predetermined points and, after the carrier has been moved thereby the required distance, is permitted to escape through the same pipes, the admission to and discharge from these pipes being controlled by an automatic valve the operation of which will be hereinafter described.

The shooting and rinsing spindles 37 and 38 carried by the pan or hopper 52 are raised and lowered after each actuation of the bottle carrier by means of hydraulic cylinders 53 upon which the hopper is supported. These hydraulic cylinders, preferably two in number, each comprise, as shown in Fig. 5, a pair of telescopic tubes 54 and 55. The tube 54 is stationarily mounted upon the base of the machine, its lower end extending into a hollow pocket or recess 56 formed in the base and its upper end being opened to receive the tube 55 which is adapted to move up and down in the stationary tube. The pan or hopper 52 is provided with encircling portions 57 surrounding the upper ends of the tubes 55 and resting upon the annular shoulders 58, so that the hopper will be carried up and down with the tubes 55. Water under pressure is admitted to the closed pocket 56 through a pipe 59 branched to supply each raising and lowering cylinder and communicating with an automatic controlling valve, the pressure of the water in the tubes 54 serving to elevate the tubes 55 and project the shooting and rinsing spindles into the bottles positioned in the upper travel of the carrier. In order to limit the elevation of the spindles, the tube 54 is provided with an annular passage 61 and a sleeve 62 is positioned inside the tube 54 and provided with a series of perforations 63 through which communication may be established between the interior of the tube 54 and the passage 61. The lower end of each tube 55 is equipped with a piston or packing ring 64 to prevent leakage between the tubes 54 and 55 and, when the tube 55 is elevated by the pressure of the water thereunder sufficiently to uncover the perforations 63, the water will escape through the passage 61 and the pipe 65 to the reservoir or compartment 16. Thus provision is made

for automatically limiting the elevation of the spindles.

The hopper or pan 52 comprises, as shown in Fig. 3, an upper hopper portion 66 having flaring walls and adapted to collect the water discharged from the bottles being cleansed and a lower water chamber 67 from which water is supplied to the shooting spindles. Water under pressure is delivered 10 to this chamber at intervals from the herein-before-mentioned controlling valve through a pipe 68 delivering into a chamber 69 formed in the base 53. Telescopic tubes 71 and 72 permit the water to be delivered 15 under pressure from the chamber 69, suitable packing 73 being provided to prevent leakage between the tubes. The water is admitted to the water chamber 67 and the shooting spindles 37 just as the spindles enter 20 the mouths of the bottles and is shut off just as the spindles are emerging from the bottles by means of the automatic controlling valve which will be later described in detail. Water under pressure is also admitted at intervals 25 to the rinsing spindles 38 through a supply pipe 74 from any suitable source of clear water, the admission to the rinsing spindles being also controlled by the automatic controlling valve. Both the shooting 30 and rinsing water discharged from the bottles being cleansed is collected in the hopper 56, from whence it overflows through the telescopic overflow pipes 75 into the reservoir 16, the same water being delivered repeatedly 35 to the carrier actuating cylinder, to the shooting spindles and to the raising and lowering cylinders.

The hopper 66 is also equipped with a series of cups or packets 76, each being disposed around the base of one of the shooting spindles and being adapted to contain a quantity of shot, cut wire, or other suitable material which is delivered to the interior of the bottles, for cleansing the same, through the shooting spindles. By reference to Figs. 6 and 7, in which one of the shooting spindles is shown on an enlarged scale, it will be observed that the cup 76 is provided with a downwardly extending tube 77 which projects into the water chamber 67. The lower end of the tube 77 preferably extends entirely through the floor of the water chamber 67 and is secured in position by a lock-nut 78 or other suitable means. Within the bottom of the packet 76 there is threaded a triple or nozzle 79 having a bore aligned with the bore in the extension 77. The upper portion of the nozzle terminates in a tapering projection 82 and at the base of this projection there are provided a plurality of diverging discharge orifices 81 through which the water under pressure is delivered from the chamber 67. The shooting spindle itself is carried by a yoke 83 threaded onto the nozzle 79, the yoke having an orifice 84

through which the tapered projection of the nozzle extends. The base of the yoke is also hollowed out to form a passageway 85 through which the water discharged from the orifice 84 is delivered to the orifice 82. The unobstructed portion of the orifice 84 surrounding the tapered projection 82 is preferably of a smaller size than the shot or other material held by the cup 76 to prevent the shot or similar material from falling 75 into the water chamber 67. In case an exceptionally small particle of solid matter should fall through the orifice 84 it will be retained at the bottom of the passageway 85 and subsequently discharged through the orifice 84 when the pressure is again turned on. It will be observed that the lower end of the shooting spindle 37 is held by the yoke 83 directly above and in alignment with the discharge orifice 84, so that when water under pressure is delivered from this orifice it will discharge directly into and through the shooting spindle and the injector action at this point will carry a portion of the shot or other solid material contained in the cup 76 along with the water into the bottle to be cleansed. From Fig. 6 it will be apparent that the shot discharged from the bottle will be collected by the flaring portion 36 of the bottle socket immediately beneath the bottle 85 and will be returned to the cup 76, the water discharged from the bottle in the meantime overflowing into the hopper portion 66 from which it is delivered to the reservoir 16 as previously described.

The controlling valve, designated generally by reference character 86, to which the pipes 51, 59, 68 and 74 hereinbefore mentioned, are connected, will now be described: Referring to Figs. 8 to 14, inclusive, it will be observed that the valve comprises a cylindrical casing 87 having closed ends 88 and 89. Within the casing there is mounted the valve member 91 adapted to revolve within the casing to intermittently open and close the various ports through which water is to be discharged from the casing. The valve member is substantially cylindrical in shape, open at one end and partially closed at the other and has a longitudinally extending partition 92 which divides the valve member throughout a portion of its length into two compartments. Gear teeth 93, adapted to mesh with a worm 94, are provided on the periphery of the valve member intermediate its end and through this driving connection a continuous rotation of the valve member is effected from the continuously rotating shaft 95 upon which the worm 94 is mounted. Water under pressure is continuously supplied to the interior of the valve member through a pipe 96 connected with a rotary pump 97, or other suitable mechanism for supplying water under pressure. A port 98, Figs. 9 and 10, is formed in the walls of the 130

valve member in alignment with the pipe 59 leading to the raising and lowering cylinders through which communication is established between the interior of the valve member and the raising and lowering cylinders as the valve member revolves. Water under pressure is thereby admitted to the cylinders 53 to raise the spindles, as hereinbefore described. A second port 99, formed 10 in the valve member in alignment with the pipe 59, permits the water to escape from the cylinders 53 to the valve compartment separated from the water under pressure by the partition 92, the water being permitted 15 to escape from the open end of this compartment to the reservoir 16 through the discharge pipe 101. From Fig. 10 it will be apparent that, as the valve member rotates in the direction of the arrow, water under pressure will first be admitted from the interior 20 of the valve member through the port 98 to the cylinders 53 and subsequently permitted to discharge therefrom through the port 99. It is desirable that the water be turned on 25 to the spindles as soon as they enter the mouths of the bottles and to this end I have provided in the valve member 91 a port 102 adapted upon rotation of the valve member 30 to establish communication between the interior of the valve member and the pipe 68 leading to the water chamber 67. The port 102 is of sufficient length to permit water to 35 be supplied to the spindles from the time that they enter the mouth of the bottle until 40 they are withdrawn therefrom on their lowering movement. Simultaneously with the admission of water to the shooting spindles it is desirable to admit water to the rinsing spindles, but the rinsing water must be fresh 45 and clean and, therefore, it is derived from a fresh water supply. A pipe 103 communicating with any suitable source of fresh water supply enters the top of the casing 87 adjacent the pipe 74 and a circumferential 50 groove or channel 104 is formed on the periphery of the valve member 91 in alignment 55 with the ports through which pipes 74 and 103 communicate with the interior of the casing. It will be apparent that as the valve member revolves communication will be established between pipes 103 and 74 so that 60 clean fresh water under pressure will be supplied to the rinsing spindles at the same time that water is supplied to the shooting spindles through the pipe 68.

After the supply of water to the shooting and rinsing spindles has been shut off and the spindles have been lowered to normal inoperative position, water under pressure is admitted to the forwarding or carrier actuating cylinders 44 through the pipe 51 to move the bottle carrier forward a step. To this end a port 105 is provided in the valve member 91 which establishes communication 65 between the interior of the valve member

and the pipes 51 to cause the hydraulic cylinders 44 to move the carrier forward a step before the port 98 is brought into registration with the pipe 74 to raise the spindles and an outlet port 106 is provided through 70 which the water is discharged from the cylinders 44 as the water is admitted to the normal position by the expansion springs 47. The pump 97 is continuously operated from a coaxially mounted motor 107, or other 75 suitable source of power, and the shaft 95 is continuously rotated by a worm and gear connection 108 between the shaft 95 and the shaft 109.

From the foregoing it will be apparent 80 that the pressure pump 97, which takes its suction from the reservoir 16, and the controlling valve are continuously operated. The continuous rotation of the controlling valve causes water under pressure to be admitted 85 to the raising and lowering cylinders 53 to raise and lower the shooting and rinsing spindles. Just before the shooting spindles enter the bottles water is admitted thereto from the controlling valve and simultaneously clean fresh water is admitted 90 to the rinsing spindles 38. As the spindles leave the mouths of the bottles on their downward movement the supply of shooting and rinsing waters is shut off and after the 95 spindles have been lowered to normal inoperative position the water is admitted by the controlling valve to the forwarding or carrier actuating cylinders 44 to move the carrier forward a step, the water in the 100 cylinders 44 being permitted to subsequently discharge through the controlling valve as the actuating mechanism is returned to normal position by the expansion springs 47. The bottles are placed in the sockets at the 105 left end of the machine, viewing Figs. 1 and 2, and as they travel across the machine they are subjected to a series of shooting operations and a rinsing operation, all of the operations of the machine and the cleansing 110 of the bottles being effected automatically and without necessity of any manual control by the operator who need only place the dirty bottles in the sockets at one end of the machine and remove the clean bottles from 115 the other end. The carrier is located entirely above the shooting and rinsing spindles thereby reducing the length of the carrier and the size of the machine to a minimum and the raising and lowering, the 120 washing and rinsing and the forwarding operations are all performed automatically and by hydraulic means, thereby eliminating from the machine the friction, noise and wear incident to a multitude of moving mechanical parts which have heretofore been considered necessary in machines of this general character.

While I have shown and described a preferred embodiment of my invention it will 125

130

be understood by those skilled in the art that many variations from the exact structure disclosed may be resorted to without departing from the spirit of the invention or sacrificing any of the material advantages thereof.

I claim:

1. In a bottle washing machine, the combination of an endless conveyer comprising parallel runs, open sockets adapted to receive the necks of bottles, carried thereby, reciprocatory washing spindles held against lateral movement in proximity to one of said runs, and means for projecting said spindles through both runs into the bottles held in the socket of the run more remote from the spindles. 50
2. In a bottle washing machine, the combination of an endless conveyer comprising parallel runs, open sockets adapted to receive the necks of bottles, carried by said runs, reciprocatory washing devices held against lateral movement in proximity to one of said runs, means for projecting said devices through both runs into the bottles carried by the more distant run, and means for advancing the conveyer when the spindles are in retracted position. 60
3. In a bottle washing machine, the combination of an endless carrier provided with bottle receiving sockets, means for alining the sockets on the two travels of said carrier, a plurality of washing spindles, and means for projecting said spindles through 70 said alined sockets.
4. In a bottle washing machine, the combination of an endless carrier having the two travels thereof disposed in proximity to each other, a plurality of washing spindles normally disposed adjacent one travel of the carrier, and means for projecting said spindles through both travels of said carrier. 75
5. In a bottle washing machine, the combination of an endless carrier, means for intermittently actuating the same, a plurality of washing spindles normally disposed outside the perimeter of said carrier, and a plurality of bottle receiving sockets 80
- mounted on said carrier, said sockets being provided with slots to receive the ends of said spindles whereby to permit actuation of the carrier with the ends of the spindles disposed inside the plane of the ends of said sockets. 85
6. In a bottle washing machine, the combination of a row of reciprocatory washing spindles, and a carrier movable transversely to said row of spindles and having a corresponding row of bottle sockets adapted to register with said spindles, said sockets having longitudinal slots disposed in alinement with the spindles in the direction of movement of the carrier to permit the sockets to move across the ends of the spindles. 90
7. In a bottle washing machine, the combination of a reciprocatory washing spindle, and a carrier movable transversely to said spindle and having a bottle socket adapted to register with said spindle, said socket having longitudinal slots disposed in alinement with the spindle in the direction of movement of the carrier to permit said socket to move across the end of the spindle. 95
8. In a bottle washing machine, the combination of a shotting spindle, a yoke supporting said spindle and provided with a delivery orifice positioned in alinement with the bore of said spindle, and a supply nozzle having a tapered projection protruding through said orifice. 100
9. In a bottle washing machine, the combination of a cap adapted to contain shot, or the like, a nozzle mounted in said cup and having an upwardly projecting tapered portion, said nozzle being provided with discharge orifices below said tapered portion, a yoke provided with a cavity in communication with said nozzle orifices and having a discharge orifice disposed around the projecting portion of said nozzle, and a shotting spindle carried by said yoke with its bore in alinement with said discharge orifice. 105
